CLAIM

The ornamental design for a closing plug for a container-installed flange, as shown and described.

DESCRIPTION

FIG. 1 is a top, front, and right side perspective view of a closing plug for a container-installed flange showing the new design;

FIG. 2 is a top plan view thereof;

FIG. 3 is a bottom plan view thereof;

FIG. 4 is a front elevation view thereof; and,

FIG. 5 is a side elevation view thereof, with the opposite side appearing the same.

The portions of the design shown in broken lines form no part of the claim.
